Primary Examiner — Bridget L Eland(74) *Attorney, Agent, or Firm* — Klemchuk LLP; Kirby B. Drake(57) **CLAIM**

The ornamental design for an implant insertion device, as shown.

DESCRIPTION

FIG 1 is a perspective view of an implant insertion device showing my new design;

FIG. 2 is a right side view thereof;

FIG. 3 is a left side view thereof;

FIG. 4 is a back view thereof;

FIG. 5 is a front view thereof;

FIG. 6 is a top view thereof; and,

FIG. 7 is a bottom view thereof.

1 Claim, 5 Drawing Sheets(56)
